UNITED STATES PATENT OFFICE.

GEORGE F. WOLFE, OF NEW YORK, N. Y., ASSIGNOR TO UNITED SHOE MACHINERY COMPANY, OF PATERSON, NEW JERSEY, A CORPORATION OF NEW JERSEY.

EDGE GAGE FOR STOCK-FITTING MACHINES.

1,030,631.

Specification of Letters Patent.

Patented June 25, 1912.

Application filed February 15, 1911. Serial No. 608,811.

To all whom it may concern:

Be it known that I, GEORGE F. WOLFE, a citizen of the United States, residing at New York, in the county of New York and 5 State of New York, have invented certain new and useful Improvements in Edge Gages for Stock-Fitting Machines; and I do hereby declare the following to be a full, clear, and exact description of the invention, 10 such as will enable others skilled in the art to which it appertains to make and use the same.

The present invention is an improvement in stock fitting machines and more particularly in edge gages for use on machines of this type.

With the edge gages in general use, it is difficult to feed the sole as the work engaging surface of the gage has to be small 20 enough to enter the smallest radius in the periphery of any sole to be operated upon. With such a small work engaging surface a soft sole is indented by the gage and this causes the correct position of the sole to be 25 lost. This objection to the gages now in use is principally noticeable when operating upon insoles which are often of soft material, but it is also found in some outsoles, particularly cäcks which are irregular in out- 30 line and in which the curves are sharp. If the bearing surface of the gage is made with a large radius to prevent indenting the sole, it will not enter the sharp curve at the shank and relation of the tool to the sole edge is 35 lost.

It is the object of this invention to remedy these difficulties. In accordance with this object a feature of the invention comprises the provision of an edge gage having 40 a plurality of adjustable sole engaging points with means for relatively adjusting these points to conform to the sharpest curve at the shank in the particular style of sole being operated upon. In the best form of 45 the invention known to the inventor, the gage bar is provided with three sole engaging rolls and means for adjusting the two outside rolls with respect to the central roll so that the line of contact of these rolls with 50 the sole may be made to conform to the shank curve of the smallest radius.

The invention will best be understood from the following description and accompanying drawings and will be particularly 55 pointed out in the appended claims.

The preferred embodiment of the invention is illustrated in the accompanying drawings, in which—

Figure 1 is a plan view of the improved edge gage in operative relation to a sole; 60 Fig. 2 is a side elevation, on an enlarged scale, of the two outer movable rolls; Fig. 3 is a side elevation of the gage with the adjustable rolls removed; and Fig. 4 is a section on the line 4—4 of Fig. 1. 65

In the embodiment of the invention illustrated in the drawings the gage bar 1, which is of suitable form to be employed on a machine for performing one of the various stock fitting operations, carries a freely rotatable roll 2 mounted in a support 3. Two similar rolls 4 and 5 are mounted in the forked ends of a block 6 which is adapted to slide upon a tongue 7 on the bar 1. The slot 8 formed in the block 6 by the roll carrying forks receives the roll support 3 so that the rolls 4 and 5 are at each side of the roll 2. A shoulder screw 9, threaded into the bar 1, engages a slot in the block 6 and assists in guiding the block in its in and out movements. 75

The means for adjusting the rolls 4 and 5 may consist of a screw 10 having a knurled thumb nut 11 and a stem 12 rotatably fixed in the bar 1 by means of a groove in the 80 stem and a pin 13. The screw 10 engages a tapped hole 14 in the block 6. 85

In the use of this edge gage the operator will turn the thumb nut 11 until the rolls 4 and 5 touch the sole when the roll 2 is at the 90 surface having the greatest concavity on the periphery of the sole of the style to be operated upon. On some styles of men's shoes it will be possible to have the three rolls nearly in a straight line. On soles having sharp 95 concavities in their periphery, which are the most difficult to feed, the three rolls will be so adjusted that the curvature of their longitudinal contact surface will be substantially parallel to the sharpest concavity of the sole edge, thereby giving the greatest freedom of movement to the sole. When a change is made in the style of sole being operated upon, the gage is again adjusted so that the same conditions prevail. In each 100 instance the gage presents a large bearing surface to the sole edge but in turning the sole the sharp curves are easily negotiated and the proper working position of the sole 105 is maintained.

2

An example of stock fitting machines wherein the present invention may be employed may be found in the United States patents to Beckman Nos. 550,402 and 5 644,571, both of which illustrate gages having the defects overcome by the present invention. This edge gage is not, however, limited in its use to machines for performing the channeling operation, as it may 10 readily be adapted by a skilled mechanic to use in connection with any machine wherein it is desired to locate a sole by its edge relative to any particular tools for operating thereon.

15. While one particular embodiment of the invention has been illustrated and described, it is to be understood that the invention is not limited thereby, the scope of the invention being set forth by the claims.

20. What is claimed as new, is:—

1. An edge gage for machines for operating on soles having a plurality of sole edge engaging points adjustable to conform to the concaved portions of the sole edge, substantially as described.

2. An edge gage for machines for operating on soles having sole engaging rolls and means for relative adjustment thereof to present a longitudinal contact surface substantially parallel to the concaved portions 30 of the sole edge, substantially as described.

3. An edge gage for machines for operating on soles having a fixed sole engaging roll, a movable sole engaging roll on each side of the fixed roll, means for adjusting 35 the last named rolls with respect to the first, and means for holding the rolls in fixed relation during the operation on the sole, substantially as described.

4. An edge gage for machines for operating on soles having three alined sole engaging points, and means for adjusting the two outer points relative to the central point to present a curved longitudinal contact surface for engaging the sole edge, substantially as described.

GEORGE F. WOLFE.
